UNITED STATES PATENT OFFICE.

WILLIAM A. OLEEN AND OLOF H. OLEEN, OF COLUMBIA CITY, OREGON.

DOOR OPENING AND CLOSING MECHANISM.

1,333,567.

Specification of Letters Patent. Patented Mar. 9, 1920.

Application filed September 22, 1919. Serial No. 325,508.

To all whom it may concern:

Be it known that we, WILLIAM A. OLEEN and OLOF H. OLEEN, citizens of the United States, residing at Columbia City, in the county of Columbia and State of Oregon, have invented new and useful Improvements in Door Opening and Closing Mechanism, of which the following is a specification.

10 This invention relates to improvements in door opening and closing mechanism and the principal object of the invention is to provide means for opening the door and holding it open until the vehicle passes 15 through the same, when the door is shut.

The present invention is an improvement over that granted to us on June 18, 1918, No. 1,270,052.

20 The present invention has for its objects the simplification of the arrangement of parts shown in the said patent, the provision of means for holding the door open without the use of a bolt and means for preventing the door from closing too soon when the vehicle is passing from the building.

Still another object of the invention is to provide adjustable means connecting the two doors together so that one door will move in unison with the other door.

30 The invention also consists in certain other features of construction and in the combination and arrangement of the several parts, to be hereinafter fully described, illustrated in the accompanying drawings 35 and specifically pointed out in the appended claims.

In describing our invention in detail, reference will be had to the accompanying drawings wherein like characters denote 40 like or corresponding parts throughout the several views, and in which:—

Figure 1 is a perspective view of the invention, showing the same connected with a pair of horizontally swinging doors.

45 Fig. 2 is a plan view with the doors in closed position.

Fig. 3 is a like view with the doors in open position.

Fig. 4 is a detail view showing the means 50 for locking the doors in closed position.

Figs. 5 and 6 are detail views of the mechanism outside of the garage.

Fig. 7 is a detail view of the means for connecting the doors together.

55 In these views, A indicates the walls of the garage, and B and B' indicate the doors

thereof. These doors are connected together by means of the rod 1, one end of which is connected with the door B and its other end telescopes into the tube 2 which is connected 60 with the arm 3 carried by the door B'. A clamp 4 surrounds the split end of tube 2 so as to clamp the tube and rod together.

It will be seen by this arrangement that the two doors will move in unison. The 65 doors are held in closed position by means of the bolt 5 carried at the lower end of one door and held in engagement with the keeper 6, located in the floor, by the spring 7. A handle 8 passes through said door and 70 its inner end is connected with the bolt by the connection 9. By turning the handle, said connection will be caused to raise the bolt out of its keeper so that the doors may be opened.

A wheel operated member 10 is located in front of the garage at a suitable distance therefrom and a similar member 11 is located within the garage. These members are in alinement and are located to one side 80 of the door opening. The operating rod 12 connects these two members together and said rod has an operating link 13 at each end thereof for engaging the rollers 14 connected with said members. The members and operating members are similar to the like elements described in the before mentioned patent and these parts will not be described in detail. A spring 15 normally holds the inner member 11 in upright position as described in said patent. Within the building adjacent the door opening is pivotally mounted a lever 16 which is intermediate its ends, connected with the operating bar 12. We prefer, however, to form this operating 95 bar of two parts with its inner ends pivoted to said lever. The outer end of the lever 16 carries an eyebolt 17 through which passes a rod 18. Collars 19 are secured to said rod by thumb screws or the like, on each side of 100 said lever and springs 20 are placed on said rod between the eyebolt and the collars. This rod 18 is pivotally secured to a rocking lever 21 which is pivoted to a bracket 22 secured to the inner face of the door B. 105 This bracket has a pair of ears 23, which limit the rocking movement of the lever 21. The bracket also is provided with an arm 24 which is provided with an outwardly curved part so that the end of the arm is 110 spaced from the wall of the building when the door is in closed position. The curved

115

part of the arm is slotted so as to freely receive a rod 25 which is pivoted to the end of the lever 21 and carries a spring 26. This spring presses against the arm and a 5 collar 27 on the rod and tends to hold the lever against the outer ear 23. The free end of lever 21 is connected with the bolt 5 by the connection 28 in such a manner that when lever 16 is moved against the inner 10 ear said connection will be caused to lift the bolt out of its keeper to permit the doors to be opened.

It will thus be seen that when the wheel 15 operating members are moved to shift the operating rod 12 outwardly, the lever 21 will also be moved to cause its springs to move the rod 18 toward the door. The first part of this movement will depress lever 21 to cause the connection 28 to raise the bolt 20 and the rest of the movement will swing the doors open.

As the doors reach the limit of their movement outwardly a latch 29 carried at the end of the arm 24 will pass over a keeper 30 carried 25 by the rod 18 and drop behind said keeper and thus prevent the doors from closing again. Thus the doors will remain open until the operating rod 12 is moved in the opposite direction to shift the rod 18 and thus remove the keeper 30 from engagement 30 with the latch 29. The rod 18 can move sufficiently to release the latch from the keeper without moving the doors as in this movement the lever 21 will swing inwardly 35 against the tension of the spring. Further movement of the rod 18 will swing the doors closed and they will be locked in this closed position by the catch 5 engaging its keeper.

40 The springs 20 act as shock absorbers and prevent damage to the parts and to the doors.

The link 13 at the outer end of the operating bar, is of greater length than the link 45 at the inner end thereof and this outer link, at its upper edge carries a pair of projections 31 which are located adjacent the ends of the link. The wheel 14 of the outer member 10 carries a loop member 32 which embraces 50 the upper part of the link and is adapted to strike the projections 31 so that its position on the link will be changed. A notch 33 is formed in the upper part of the link and is adapted to be engaged by said 55 loop member in one position thereof.

When a car is to enter the garage the front wheel striking the outer member 10 will tilt the same and as the wheel 14 is in the outer end of the link 13 this tilting 60 movement will move the operating bar outwardly to cause the lever 16 and its attached parts to unbolt and swing open the doors. The doors are held in open position by the latch 29 engaging the keeper 30 as before 65 described. The member 10 will assume its

upright position as soon as the front wheel passes over the same, due to the weight of the wheel and its carrying part and also the weight of the operating bar resting on said wheel. As the rear wheel strikes this member it will simply tilt without moving the parts after the bar 12 has been shifted so that the wheel 14 will work in the link without further movement of the bar. The car may pass through the doors into the garage 70 and as the front wheel strikes the inner member 11, said member will tilt so that its wheel engaging the link will cause said operating bar to assume its original position and thus move the doors to the closed position and release the bolt to permit the same to engage its keeper. The spring 15 will return the member 11 to operative position after the front wheel passes the same. When it is desired to use the car again the 75 car is moved backwardly toward the doors so that its front wheel will pass over the member 11 and tilt it in a direction toward the doors. This will move the operating bar so as to cause the lever 16 and its attached parts to unlock the doors and swing them to open position. As the car is backed through the doors, the rear wheel will pass over the outer member 10 but due to the length of the outer link the wheel 14 of said 80 wheel member will lie about midway of the ends of the link so that the movement of the member will not move the bar, however as said wheel 14 moves toward the inner end of the link the loop member 32 will strike the inner projection 31 and thus be forced over to a position where its looped end will be directed toward the outer end of the link. After the rear wheel passes beyond the member, said member will assume its 85 upright position and in this movement the loop member 32 will be brought into engagement with the notch 33, and as the front wheel 90 tilts the member 10 said loop member will move toward the door and due to its engagement with the notch in the link will move the operating bar inwardly and thus close the doors.

It will be seen that the links 13 at the ends of the operating bar are of special importance as by means of these links the operating members 10 and 11 can, after opening or closing the door, return to the upright position without moving the operating bar. Also these links permit the door to be 100 opened or closed by hand without interfering with the operation of the device. These links also make it possible for the front or rear wheels to pass over the operating members after the passage of the other wheel 105 without again operating the mechanism. By means of the loop member 32 there is no danger of the doors closing too soon and thus striking the automobile. This is important where a side walk runs in front of 110

70

a garage and it is necessary to place the wheel operating member in the space between the walk and the street. This will place the operating member so near the garage that as the rear wheels are passing over said member operating the mechanism, the doors would close before the vehicle was entirely out of the garage. By the new arrangement of parts, however, the rear wheel 10 will pass over the operating member without closing the doors and said doors will not be closed until the front wheel passes over the member.

It is thought from the foregoing description that the advantages and novel features of our invention will be readily apparent.

We desire it to be understood that we may make changes in the construction and in the combination and arrangement of the 20 several parts, provided that such changes fall within the scope of the appended claims.

What we claim is:—

1. A door opening and closing mechanism 25 comprising a pair of wheel operated members located one on each side of the door, an operating rod connected with said members, a reciprocating rod yieldingly connected with the operating rod so as to be 30 moved thereby, a lock for the door, means connected with said reciprocating rod for actuating the lock and move the door, and means on said reciprocating rod for holding the door in open position.

2. A door opening and closing mechanism 35 comprising a pair of wheel operated members, an operating rod connecting the two members together, means connected with said rod for opening and closing the door and means associated with the outer wheel

40 operated member for permitting the first wheel of the outgoing vehicle to actuate said member without closing the door but setting said means so that the second wheel 45 will actuate the member and close the door.

3. A door opening and closing mechanism

comprising an inner and outer wheel operated member, an operating rod connecting said members together, a rocking lever connected with said rod, a reciprocating rod 50 yieldingly connected with said lever, spring means for yieldingly connecting said reciprocating rod to the lever, a bracket connected with the door, a lever pivoted to said bracket, a lever pivoted to the bracket and 55 connected with the reciprocating rod, ears on the bracket for limiting the movement of said member, spring means for holding the lever in its inner position, a bolt for the door having a connection between said bolt 60 and said lever.

4. A door opening and closing mechanism 65 comprising inner and outer wheel operated members, an operating rod connecting the members together, a rocking lever actuated by said rod, a reciprocating rod yieldingly connected with said rod, means connecting said reciprocating rod with the door, an arm carried by the door, a latch on said arm and a keeper on the reciprocating bar for 70 engaging said latch to hold the door in open position.

5. A door opening and closing mechanism 75 comprising a pair of wheel operated members, rollers carried thereby, a depending part on the outer member for the roller, an operating bar having links at its ends receiving said rollers, door operating means actuated by said rod, projections on the upper edge of the outer link and a notch in 80 said upper edge adjacent the outer end of the link and a loop member connected with the wheel and adapted to engage with said projections so as to be changed from one position to the other and to engage the 85 notch for moving the operating rod inwardly in one position of the parts.

In testimony whereof we affix our signatures.

WILLIAM A. OLEEN.
OLOF H. OLEEN.
